AUTOMATIC IGNITION CUTOFF SYSTEM

Charles N. Reavis, Raleigh, N. C.

Application April 18, 1941, Serial No. 389,260

5 Claims. (Cl. 123—198)

My invention relates to improvements in means for protecting automobile and other internal combustion engines by automatically cutting off the ignition and thereby stopping the engine whenever a failure of the lubrication system or lack of oil therein occurs or when the water in the cooling system falls below a safe level, and the primary object of my invention is to provide such means in simple and practical form adapted for easy installation.

Another important object of my invention is to provide a system of the character indicated which is adapted for connection in the primary ignition circuit without the cutting of any of the wires thereof or other disarrangement of the usual disposition and functioning of the ignition system.

Other important objects and advantages of my invention will be apparent from a reading of the following description of the appended drawings, wherein for purposes of illustration, a preferred embodiment of my invention is shown.

In the drawings:

Figure 1 is a fragmentary longitudinal vertical sectional view taken through the motor compartment of an automobile and showing adaptation of the present invention.

Figure 2 is an enlarged longitudinal sectional view taken through the casing of the oil failure responsive component of the invention, and fragmentarily through the casing of the cooling medium affected component, and showing diagrammatically their electrical connections to the ignition system.

Figure 3 is a fragmentary horizontal sectional view taken through Figure 2 along the line 3—3 and looking downwardly.

Figure 4 is an enlarged fragmentary vertical longitudinal sectional view taken through the lower right hand portion of casing 6 of Figure 2.

Figure 5 is a side elevational view of the cooling medium affected component, and

Figure 6 is a right hand end elevational view of Figure 5.

Figure 7 is an enlarged longitudinal sectional view taken through the casing of the water failure responsive component of the invention.

Referring in detail to the drawings, the numeral 5 generally designates the oil pressure failure responsive unit which involves a suitable metal casing 6 preferably in rectangular form for mounting on and grounding to the front of the dashboard 7 or other suitable place in the motor compartment 8. A fitting 9 depending from the bottom of the casing 6 is arranged for

connection to the motor lubricating system oil pressure line 10. Inside the casing 6 an oil pressure responsive bellows 11 has its lower end connected in communication with the fitting 9. The upper end of the bellows has a lug 12 inserted upwardly in the opening 13 in the horizontal insulated arm 14 which is pivoted at 15 on a lug 16 on one end of the casing 6. A stop lug 14' to limit upward movement of the arm 14 projects from the back of the casing. Between the hole 13 and the pivot 15 a vertical eye bolt 17 traverses the arm 14 and has a contractile spring 18 stretched between its eye and an anchor 19 on the bottom of the casing. The free end of the said arm is notched at 20 to freely accept the lug 21 on the adjacent end of the casing to steady the operation of the arm. A binding post contact 22 traverses the arm 14 adjacent the said free end for electrical engagement with a companion stationary binding post contact 23 which is mounted through a lug 24 on the adjacent end of the casing. An insulated binding external post 25 traverses the same end of the casing and is connected to the contact 23 by a bar 26.

The binding post contact 22 on the arm 14 is connected by a flexible wire 27 to an insulated external binding post 28 traversing the right hand end of the casing 6 below the lug 16. A horizontal helical electrical heating element 29 is suspended between a post 29' electrically connected to the casing 6, and hence grounded, and the binding post 28.

Horizontally supported immediately below the heating element is the time delay element comprising a pair of bimetallic strips 30 and 31. These strips are supported in vertically spaced and insulated relation on the insulating block 32 mounted on the end of the casing, with their contact terminals normally spaced at a distance of about $2\frac{1}{2}$ inches. The lower strip 31 is connected by a wire 31' to the external insulated binding post 33 which traverses the bottom of the casing. The upper strip 30 is grounded at 30' to the casing 6. One reason the strips are both bimetallic in character is to provide against the unwanted closing of the strips during an onset of warm weather, their spacing having been adjusted for cold weather operation. By using two similar bimetallic strips the warp of the strips is similar and the original spacing automatically maintained while the heater 29 heats the upper strip 30 sufficiently to cause it to warp relative to the lower strip 31 and electrically engage their contact terminals and close the circuit therethrough.

The oil pressure failure responsive unit described above is connected in the ignition system of the motor 34 by connecting a wire 35 to a point 36 between the voltage regulator or relay 37 and the field coils of the generator 38. Another wire 39 is connected between the binding post 33 and the primary side 40 of the ignition coil 41 direct or to the ungrounded side 42 of the circuit breaker 43, whichever is more convenient. Another wire 44 connects between the binding post 28 and the ungrounded side of a suitable signal such as a bulb 45 whose office is to warn the driver, in the event of a loss of oil pressure and/or of a low cooling medium level, before the actual cut-out of the ignition system occurs, so that the driver may pull over to the curb or into a service station before the motor is rendered inoperative.

It will appear from the foregoing that whenever the oil pressure in the oil line 10 drops below the pressure for which the device is adjusted, the bellows 11 will collapse, and, aided by the spring 18 the arm 14 will subside from an elevated position to the depressed position shown in Figure 2 of the drawings and engage the contacts 22 and 23. This energizes the heater 29 and operates the signal 45. After the predetermined time delay, such as 45 seconds, the strips 30 and 31 close and thereby cut off the current supply to the circuit breaker 43 and the ignition coil, thereby stopping the motor.

The connection of the wire 35 is made at the described point to insure the inoperativeness of the device when the motor is idling at a low speed and oil pressure is below normal, as in waiting for a traffic light or while parked, and at such a low speed as to fail to turn the generator fast enough to close the points in the voltage regulator or relay 37. It is to be observed that the connections to the circuit breaker and/or the primary of the ignition coil are made simply by loosening the binder nuts and retightening them, thereby eliminating any cutting of wires or other damage or change to the original condition of the ignition system.

The cooling medium affected component which is generally designated 50 comprises a suitable, preferably rectangular casing 51 which may conveniently be mounted on the head of the motor 54 of the radiator 55. On the inside of one end of the tank is fixed a dielectric block 56 through which project the short upper binding post 57 and the longer lower binding post 58. The contact 59 is connected by a wire 59' with the binding post 28, while the contact 60 is connected by the wire 73 with the wire 35. The inner ends of these binding posts and corresponding portions of the block 56 are longitudinally staggered to support spaced vertical spring contact fingers 59 and 60 which have facing contacts on their upper ends.

A hinge 61 mounted on the bottom of the casing 51 near the block 56 constitutes the pivotal support for the tiltable, generally rectangular tank 62 to whose adjacent lower corner the hinge is attached. When normally full of cooling medium from the radiator tank 54 the tank 62 rests upon a felt mat 63 on the bottom of the casing 51.

A contractile spring 64 is stretched between the eye 65 on the casing end and the eye 66 on the slanted tank end whereby the tank 62 is tilted upwardly in a left hand direction whenever the cooling medium in the radiator tank 54 subsides

below a selected level and cooling medium leaves the tank 62 by the drain pipe 67.

The tank 62 is located at such an elevation that the bottom of the tank 62 will be near or above or below the bottom of the radiator tank 54 but always above the level of the head of the motor 34, so that whenever through any cause the level of the water in the radiator and radiator tank 54 goes below the predetermined point the tank 62 will be substantially emptied of cooling medium and pulled up into tilted position by spring 64. A rigid adjustable linkage 68 operatively connects the adjacent end of the tank 62 with the spring contact element 69 so that the contact element is engaged with the contact element 59 in the up-tilted position of the tank and separated from the contact element 59 in the normal horizontal position of the tank 62.

Fluid connection with the tank 62 are provided by the upper and lower tubes 69 and 67, respectively, which project from the side wall of the tank through slots formed in the side wall of the casing 51. The casing has a removable cover. The lower or gravity drain tube 67 is connected by a hose 70 to a depressed part of the cooling system, such as the lower radiator hose 71, while the upper tube 69 is connected by a pipe 72 to the radiator tank 54 at the predetermined level.

30 The contact 60 is connected to the wire 35 at 73 while the contact 59 is connected to the binding post 28, whereby the contact points 22 and 23 are shunted when the points 59 and 60 come together when a low water condition obtains in 35 the radiator, thereby cutting off the ignition system.

Although I have shown and described herein a preferred embodiment of my invention it is to be understood that I do not wish to limit the 40 application of my invention thereto, except as may be required by the scope of the subjoined claims.

Having described the invention, what is claimed as new is:

45 1. In a device for cutting off the ignition system of an internal combustion engine, said device comprising an oil pressure failure responsive component comprising a circuit closer maintained open by normal oil pressure and adapted to close in the absence of normal oil pressure, said circuit closer having one side thereof connected to the generator of the ignition system at a point between the field coils and the voltage regulator of said generator and having its remaining side connected to the battery of said ignition system, whereby closing of said circuit closer is precluded during low oil pressure incident to idling of said engine.

60 2. A device according to claim 1 wherein said circuit closer comprises a bellows connected to the engine oil pressure line, a pivoted arm normally elevated by said bellows due to its expanded condition, a first contact on said arm, a second contact supported for engagement by said first contact only in the depressed position of said arm.

65 3. In a device for cutting off the ignition system of an internal combustion engine having a pressure oiling system, said oiling system having an oil pressure responsive element, a first normally open circuit closer connected in said system and operated by said pressure responsive element, a second normally open circuit closer connected in said system and shunting said first circuit closer, said second circuit closer comprising

ing thermostatic circuit grounding contactors arranged to close when heated, electrical heating means for said thermostatic contactors and connected in said system for energization only while said first circuit closer is in closed position, said first circuit closer being arranged to close upon a drop of the oil pressure below a predetermined level and energize said electrical heating means, thereby effecting delayed closing of said second circuit closer and grounding of the ignition circuit.

4. In a device for cutting off the ignition system of an internal combustion engine having a pressure oiling system having an oil pressure responsive element, said ignition system including a battery-generator component wherein the output of the generator to the battery is controlled by a voltage regulator, said device comprising a switch operatively connected to said oil pressure responsive element, said switch being electrically connected in said system at a point between the battery and the voltage regulator so as to be ineffective for deenergizing the ignition circuit while the engine is idling at low speed and the oil pressure is correspondingly below normal.

5. In a device for deenergizing the ignition system of an internal combustion engine having a pressure oiling system having a pressure responsive element, said ignition system including a primary circuit including a battery-generator component wherein the output of the generator to the battery is controlled by a voltage regu-

lator, said device comprising a casing supporting and enclosing said pressure responsive element, said element comprising a vertical member arranged to occupy an elevated position during 5 normal oil pressure and a depressed position during low oil pressure in said oiling system, a horizontal bar pivoted at one end on said casing with its opposite end overlying said vertical member, a first contact on and insulated from the free 10 end of said horizontal bar, a companion second contact below said first contact, said second contact being mounted in and insulated from said casing, said first and second contacts being disengaged while said vertical member is in an elevated position responsive to normal pressure in 15 the oiling system, one of said first and second contacts being electrically connected in said primary circuit at a point between the battery and the voltage regulator so that closing of the said 20 first and second contacts is ineffective to deenergize the ignition circuit while the engine is idling at low speed and the oil pressure is correspondingly below normal, a shunt circuit including an electrical heating coil in said casing and connected around said first and second contacts, a 25 pair of normally separated thermostatic contact arms lying spacedly along said heating coil and arranged to warp when said heating coil is energized and electrically engage each other after a short delay thereby effecting delayed opening of 30 said primary circuit.

CHARLES N. REAVIS.
